UNITED STATES PATENT OFFICE.

GEORGE F. S. ZIMMERMAN, OF FREDERICK, MARYLAND.

IMPROVED WASHING-MACHINE.

Specification forming part of Letters Patent No. 40,878, dated December 8, 1863.

To all whom it may concern:

Be it known that I, GEORGE F. S. ZIMMERMAN, of Frederick, in the county of Frederick and State of Maryland, have invented certain new and useful Improvements in Tub Washing-Machines; and I do hereby declare the following to be a full, clear, and exact description of the same, reference being had to the accompanying drawings, making a part of this specification, in which—

Figure 1 represents a side elevation of the washing apparatus arranged in a common wash-tub, and showing in red lines the rubber and its hinged frame as raised up and thrown back, so that the concave may be used for ordinary hand-washing, as with a wash-board. Fig. 2 represents a vertical section through the tub and washing apparatus.

Similar letters of reference in both the figures refer to like parts of the apparatus.

Several forms of washing devices have heretofore been made and patented which were designed to be used in an ordinary wash-tub. I lay no claim to any general principle that may be involved in such washing apparatus.

My invention consists in the hinging of the frame that carries the rubber to the stationary frame that stands in the ordinary tub, so that the pressure upon the clothes being washed may be regulated, the rubber thrown back to place, or remove the clothes, or to adapt the machine to hand-washing, as by a common hand-board, as may be desired.

To enable others skilled in the art to make and use my invention, I will proceed to describe the same by reference to the drawings.

A represents an ordinary hand-tub, in which the washing apparatus B stands, and from

which it may be readily removed. This washing apparatus is composed of the side pieces, *a*, and supports *b*, together with a ribbed or fluted concave, *c*, which forms the under or stationary portion of the apparatus, and a gallows frame, *d*, hinged to the supports *b* at the point *e*, said gallows-frame carrying a rocking rubber, *f*, furnished with a ribbed or fluted surface, *g*, and a handle, *h*, and these constitute the moving parts of the washing apparatus. The tub holds the apparatus firmly without fastenings, and when the clothes are to be washed the rubber *f* is raised up to properly place them, and the water having been thrown in, the operator, with one hand upon the frame *d*, regulates the necessary pressure, while with the other the rubber *f* is worked to wash the clothes. Should it be necessary to use the concave *c* as an ordinary hand wash-board, it is only necessary to throw back the frame *d*, as shown in red in Fig. 1, and then there remains the common tub and hand-board, so that machine or hand washing either may be done in the tub.

I am aware that a removable washing apparatus has heretofore been applied to a common hand wash-tub. This I do not claim; but

What I do claim as new, and desire to secure by Letters Patent, in a washing apparatus that is to be set and used in a common wash-tub, is—

The hinging of the frame *d*, that carries the rubber *f*, to the stationary or under portion, *b*, for the purpose and in the manner herein described and represented.

GEO. F. S. ZIMMERMAN.
